INTAKE MANIFOLD FOR MOTORS

Filed July 22, 1930

UNITED STATES PATENT OFFICE

ARTHUR E. KUEHN, OF PORTLAND, OREGON

INTAKE MANIFOLD FOR MOTORS

Application filed July 22, 1930. Serial No. 469,686.

This invention relates to means for varying the vacuum within an intake manifold that is applied to a delivery pipe from a carburetor and conducts explosive mixtures to the firing chambers of an internal combustion engine, in order that there may be maintained a "balanced" explosive mixture within the intake manifold at all times irrespective of any sudden movements of the throttle.

10 Prior to my present invention it was very difficult to obtain a "balanced" explosive mixture, this is, a proper proportion of air to gasoline vapor at all times especially when the throttle was suddenly opened, or suddenly closed. When the throttle was opened suddenly and the fuel stream increased, the engine misfired and choked because the explosive was too lean and "unbalanced". This is due to the difference in the inertia of the 15 fuel and the air entering the carburetor, the inertia of the fuel being greater than that of the air and therefore the ratio of the two components varies until the increased acceleration of the engine increases the velocity of 20 the fuel passing through the carburetor. When the throttle was closed suddenly and the fuel stream decreased the engine usually sputtered and backfired and permitted a substantial amount of unused explosive mixture 25 to be "spent" through the exhaust because the explosive mixture was "unbalanced".

By the use of my device it is impossible to cause choking, misfiring, or sputtering even though the present day motor fuels do not 30 vaporize readily and it is a well known fact that a large percentage of the fuel is not vaporized until it has reached the intake manifold.

It is an object of my invention to provide 35 means in an intake manifold whereby a throttle action for varying the volume therein takes place and wherein a proper amount of the explosive mixture will be maintained to satisfy the acceleration, or deceleration 40 of the engine. In other words, I desire to obtain uniformity in the character of the explosive mixture with varying loads and varying speeds of the engine.

Another object of my invention is to provide 45 a valve mechanism in the intake mani-

fold, controllable by the throttle, whereby the vacuum in the intake manifold is increased in direct proportion to the opening of the throttle and the flow of fuel is thereby properly increased.

55

A further object of my invention is to provide a valve mechanism in the intake manifold controllable by the throttle, whereby the vacuum in the intake manifold is decreased in direct proportion to the closing of the 60 throttle, and the fuel intake is decreased proportionately.

A still further object of my invention is to provide a sufficient quantity of properly prepared explosive mixture within the intake 65 manifold absolutely necessary for the proper functioning of the engine; the quantity varying with the speed and load of the engine.

A still further object of my invention is to provide means for adjusting the amount of 70 pressure to be applied to the means disposed within the intake manifold when the throttle is suddenly moved for increasing, or decreasing the flow of fuel.

A still further object of my invention is to 75 increase the operating efficiency of the carburetor.

With these and incidental objects in view, the invention consists in certain novel features of construction and combination of 80 parts, the essential elements of which are set forth in the appended claims, and a preferred form of embodiment of which is hereinafter shown with reference to the drawing which 85 accompanies and forms a part of the specification.

In the drawing:

Fig. 1 is a side view of an automotive vehicle illustrating one of my new and improved devices in place upon the inlet manifold of the engine; the device being disposed between the carburetor and the engine cylinders.

90

Fig. 2 is a side view, partially in section, of 95 one of my new and improved devices.

Fig. 3 is a sectional, end view, of the mechanism illustrating in Fig. 2, the same being taken on line 3-3 of Fig. 2, looking in the direction indicated.

Fig. 4 is a sectional, top, plan view of the 100

mechanism illustrated in Fig. 3, the same being taken on line 4—4 of Fig. 2 looking in the direction indicated.

Fig. 5 is a perspective, end view, of the 5 valve disposed within a cylinder of the inlet manifold.

Like reference characters refer to like parts throughout the several views.

My invention is primarily intended for 10 placement upon the inlet manifold of the cylinder block 1 of an automotive engine and upon which I have shown my device as being placed, but I do not wish to be limited in the use of my device for placement upon automotive engines as the same may be used with 15 equal facility upon all types of internal combustion engines. Neither do I wish to be limited in the application of my device in the specific form herein illustrated as the same 20 may be made in various forms.

In preferred embodiment I make the inlet manifold 2 elliptical in shape with substantially circular ends 3 and 4 and parallelly disposed side walls 5 and 6. Outlets 7 and 8 25 are disposed at the discharge side of the inlet manifold and have flanges 9 and 10 which are secured to the motor block by any suitable fastening means, as by fastening bolts 11. The fastening bolts pass through bolt holes 12 30 and 13 that are disposed in each of the flanges. A removable head 14 is removably secured to the upper end of the inlet manifold and a passageway 15 is disposed through one of the walls of the inlet manifold with a flange 35 16 being secured thereto. The purpose and object of the flange is to secure the same to the carburetor 17.

A valve 18 which is preferably formed of plates 19 and 20 spaced apart by leathers 21 40 and 22 is disposed within the intake manifold. A relatively tight working relationship is maintained with the walls of the inlet manifold. The valve 18 is supported upon valve stems 23 and 24 that pass through bosses 25 45 and 26 disposed upon head 14.

Supporting legs 27 and 28 extend upwardly from the head 14 and a rocker shaft 29 is journaled therein. Walking beams 30 and 31 are disposed upon the rocker shaft 29 and 50 links 32 and 33 are disposed between the valve stems 23 and 24 and the walking beams 30 and 31 with the links interposed therebetween being journaled relative thereto about journal pins 34 and 35. An operating lever 36 is 55 secured to the rocker shaft 29.

A bell crank 37 is rockably disposed upon a supporting pin 37A which is secured to the intake manifold 2. A rod 39 is secured to one end of the bell crank and leads to either 60 the foot, or hand throttle. Links 39A and 40 are secured to the other end of the bell crank 37. The link 39A is attached to the carburetor valve and the link 40 is disposed through the operating lever 36 and has its 65 free end threaded. A compressible element

as a coil spring 41 is disposed about link 40 immediately above the operating lever 36 and a nut is threadably disposed upon the free end 43 of link 40. The spring 41 may be compressed relative to the operating lever 36 to any desired tension by adjusting the nut 42. 70

It will be remembered that the valve 18 is in a tight working relationship with the inner wall of the intake manifold 2 and it will be understood that the valve 18 will lag momentarily when the throttle is opened, or closed suddenly, due to such intimate relationship between the valve and the inner wall of the manifold. This is desirable since 75 prior to the sudden opening, or closing of the throttle there is a sufficient quantity of properly prepared explosive mixture within the intake manifold absolutely necessary for the proper functioning of the engine in accordance with the R. P. M. of the engine. By the time this explosive mixture is consumed the valve has reached the position determinable by the movement of the throttle and a vacuum created so that the ratio of air passing 80 through the carburetor and the ratio of fuel 85 passing through the carburetor is equal, and the firing chambers of the engine are in position to consume the explosive mixture now entering therein from the intake manifold 90 whose volume has been varied by the actuation 95 of the throttle.

Modus operandi

Having fully described my invention its 100 operation is as follows:

It will be assumed that the starting point for the functioning of my improved manifold begins with the valve 18 at the lowest position relative to the base of the intake manifold and when in such position the engine is "idling". When the valve is in this 105 position the explosive mixture placed in the carburetor enters the intake manifold and from there into the firing chambers under normal vacuum. If the throttle is opened 110 suddenly the connection of the link 40 and the link 39A to the same end of the bell crank 37 actuates simultaneously the carburetor valve and the valve disposed within the intake manifold so that each is opened. However, due to the fact that the valve 18 is in 115 tight working relationship with the inner walls of the manifold and due to the fact that it is desirable to maintain a lag between the movement of the carburetor valve 120 and the valve 18, the spring 41 whose tension is determinable by the adjustment of the nut 42 about the link 40 takes up a sufficient amount of pull originally exerted against the link 40 by the actuation of the throttle 125 and permits the valve 18 to move upwardly at a much slower rate than the carburetor valve. It is obvious that as the valve 18 moves upwardly a substantial suction, or 130 vacuum is created within the intake mani-

fold so that the explosive mixture prepared within the carburetor enters into the intake manifold at a very abnormal speed and expands quickly so that turbulence takes place therein which assists in the further preparation of the explosive mixture which then enters into the firing chambers properly "balanced". Too much stress cannot be laid on the fact that the valve 18, which determines the amount of vacuum within the intake manifold lags so that while the vacuum of the manifold is eventually increased, the increase occurs so gradually that the initial shocks derived from the sudden moving of the throttle is offset thereby and the mixture entering the firing chamber will always be of sufficient quantity to satisfy the acceleration of the engine.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a device of the class described, in combination with a carburetor, a manifold secured thereto, a valve reciprocably disposed therein, said valve being in tight working relationship with the walls of the manifold, a pair of valve stems extending upwardly through the upper portion of the manifold, a pair of supporting legs having journal bearings disposed within their free ends disposed upon the manifold, a shaft rockably journaled within the supporting legs, walking beams secured to the ends of the shaft, links secured to the walking beams and to the valve stems, an operating lever secured to the shaft, a bell crank journaled to the manifold and having one of its arms in direct alignment with the operating lever, links associated with the same arm and with the operating lever and carburetor valve, and means secured to the other arm of the bell crank for synchronically operating the valve disposed within the manifold and the valve disposed within the carburetor.

2. Apparatus as in claim 1 wherein a spring is disposed above the operating lever and about the link disposed therethrough, whose tension is adjustable, said tension of the spring adapted to effect the rate of movement of the valve within the manifold.

ARTHUR E. KUEHN.
